UNITED STATES PATENT OFFICE

MARTIN L. WIENER, OF NEW YORK, N. Y.

BEVERAGE DISPENSING COUNTER

Application filed March 13, 1928. Serial No. 261,274.

This invention relates to counters adapted for the dispensing of beverages and the like and particularly to counters which are portable.

This invention has for its object generally to provide a counter of the character specified which is economical, commodious and readily manufactured.

More specifically, an object is to provide a counter which is collapsible, that is, one which may be folded up and set out of the way, but, when desired for use, may be set up in any convenient place and is also of a character such as to be sufficiently ornate as a piece of furniture that it may be set in a drawing room or dining room.

Other objects of the invention will in part be obvious and will in part appear herein-after.

The invention accordingly comprises the features of construction, combination of elements, and arrangement of parts, which will be exemplified in the construction herein-after set forth and the scope of the application of which will be indicated in the claims.

For a fuller understanding of the nature and objects of the invention reference should be had to the following detailed description taken in connection with the accompanying drawings, in which:

Fig. 1 is a front elevation of the counter in assembled relation constructed in accordance with the invention;

Fig. 2 shows a view of the counter in side elevation;

Fig. 3 shows a fragmentary top plan view of the counter, parts being broken away in order better to illustrate the structural features hereof;

Fig. 4 shows a side view of the counter when collapsed; and

Fig. 5 shows a fragmentary detailed sectional view of a portion of the counter structure.

Referring now to the drawings and particularly to Fig. 1, 10 denotes a front member to which rearwardly projecting side members 11 are hingedly secured by means of hinges such as shown at 12 in Fig. 3, these hinges being secured to the inside portion of the post

members 13 which are secured to the ends of the front member 10. These side members, as will be seen, swing about a vertical axis when the counter is fully set up as indicated in Figs. 1 and 2 and are adapted to provide a support extending backwardly from the front member to rest upon the floor and prevent the counter from tipping. These side members by reason of their manner of mounting on the post members 13 can be folded inwardly against the rear side of the front member so as to assume the position indicated by dotted lines at 14. This permits the folded-up counter to have a very narrow appearance when viewed in profile as indicated in Fig. 4.

In order to preserve the arcade appearance of the cabinet when viewed from the side, it is desirable that the joint of the hinged side member shall be coincident with the edge of the post 13, since otherwise a crack might appear. To this end the hinge for the side member is set back from the vertical edge of the post 13 so that the joint between the side member and the post when swung to the open position is consequently concealed by the overhanging edge of the post 13.

The top member 15 which serves as the actual counter in the device of the present invention is also pivotally secured to the front member 10 and is adapted to fold about a horizontally-disposed hinge 16 as indicated in Fig. 4. This top member is held in place when the side members have been unfolded to the position shown in Fig. 3, the side members forming the support for the same as indicated in Fig. 2. This top member may have any convenient shape and may be recessed as indicated at 17 in Fig. 3. In order that the top member 15 may freely swing to the downward position shown in Fig. 4, the top member is hinged to a fixed member 18 mounted horizontally across the top of the front member. This horizontal portion 18 is shown more clearly in detail in Fig. 5 and surmounts the same, having a sufficient width to project over the side members when folded inwardly against the front member. It is thus seen that the hinge 16 is outside the side member when folded inwardly against the front member so that the top member may be swung

downwardly as indicated in Fig. 4, without unduly straining any of the parts. The horizontal member 18 is so constructed as to have a surface flush with the top of the top member 15.

In order that the top member may have cups and glasses set thereon without danger of displacement, it is preferable that the top member should have an upstanding edge or bead as indicated at 19 around its front and sides. This bead may be discontinued at the point of junction between the horizontal member and the top member so that they may be readily bent apart, but when the top member is swung to the position shown in Fig. 2, the separate bead portions come into conjunction and form a substantially continuous bead about the upper edge.

In order to enhance the appearance of the counter construction, thus provided in the present invention, a horizontal rail 20 is mounted in front of the same, which rail may be of tubular metal or other suitable construction. In order that this rail may not cause the counter to occupy undue space when in collapsed position indicated in Fig. 4, the rail itself is pivotally attached to the front member. This is conveniently accomplished by means of a pair of parallel links 21 and 22 which are pivoted first to projecting prongs 23 and 24 that are made fast to the front member, these links connecting at their other end with similar prongs 25 and 26 associated with the rail. The latter is seen to project from a downwardly-extending pedestal or support 27 that may be mounted on the rail preferably near its ends. The rail 20 and pedestal 27 by reason of the mounting by means of parallel links may be conveniently folded up against the front member as indicated in Fig. 4 so as to occupy relatively little space. The distance which the rail and its pedestals project from the front member when in this folded-up position is seen to depend substantially upon the length of the prongs 23, 24, 25 and 26. It is obvious from the construction employed that these prongs may be made as short as convenient so that the rail can be folded to occupy substantially a minimum of space.

It will be seen that the counter device of the present invention can be made of front, side and top members to have any desired dimensions but it is preferable that these dimensions should be such that the counter shall be portable and thereby enable the same to be brought into and out of drawing rooms, dining rooms and the like as a piece of furniture and can be collapsed when desired, so as to be put away or avoid occupying useful space. The manner in which the counter is collapsed will be obvious from the above description.

It will also be obvious that the counter when set up and provided with a foot rail in

accordance with the present invention, when the foot rail is in the position shown in Fig. 2, imparts a relatively high degree of stability to the counter, so there is little danger in its tipping forward. While the link arrangement here employed for connecting the rail in a collapsible condition to the counter is not in itself a rigid structure, it is seen that this linkage shifts the centre about which the counter would be tipped when tipping forward from the floor to points above the floor, so that there is no common axis about which the counter tends to tilt.

Since certain changes may be made in the above construction and different embodiments of the invention could be made without departing from the scope thereof, it is intended that all matter contained in the above description or shown in the accompanying drawings shall be interpreted as illustrative and not in a limiting sense.

Having described my invention, what I claim as new and desire to secure by Letters Patent is:

1. In a counter for dispensing beverages and the like, and adapted to be collapsed, the combination comprising a front member having end-posts, side-members hinged to said end-posts and adapted to swing back against said front-members, a horizontal-member secured across the top of the front-member and projecting to a point substantially flush with the rear edges of said side-members when collapsed, a horizontal rail disposed across the front of said front member near the base thereof having supporting pedestals secured thereon, and a four-bar linkage adapted to secure said pedestals and rail to said front-member whereby the same may be collapsed when not in use.

2. A portable counter for dispensing beverages comprising a front member, side members hinged thereto and a top member having a hinge piece rigidly affixed with respect to the front member and extending rearwardly of the infolded side members, said top member in set up position resting near its ends upon the extended side members; a pair of pedestals, a pair of parallel-motion linkages each in a vertical plane and affixed to said front member near the lower end thereof and carrying said pedestals, and a horizontal rail affixed to said pedestals, whereby the rail may be collapsed against the panel of the collapsed counter for storage of the latter when out of use.

In testimony whereof I affix my signature.
MARTIN L. WIENER.
